CLAIM

The ornamental design for a prismatic light transmitting panel, as shown and described.

DESCRIPTION

FIG. 1 is a bottom perspective view of a prismatic light transmitting panel showing my new design, it being understood that the prismatic pattern partially shown in the upper right hand corner is uniformly continuous over the bottom surface of the lens;

FIG. 2 is a bottom plan view thereof;

FIG. 3 is a top plan view thereof;

FIG. 4 is a fragmentary bottom plan view thereof on an enlarged scale;

FIG. 5 is a fragmentary left edge elevational view thereof on a greatly enlarged scale, all edges of the panel having the same configuration;

FIG. 6 is a cross-sectional view thereof on a greatly enlarged scale as taken along line 6—6 of FIG. 4.

FIG. 7 is a fragmentary view in perspective thereof on an enlarged scale.

The panel is fragmentarily shown in FIGS. 4 and 5 for convenience of illustration.
